DISPENSING RAZOR HANDLE

Sam Rosenzweig, New York, N. Y.

Application April 26, 1949, Serial No. 89,653

2 Claims. (Cl. 128—260)

1

This invention relates to a safety razor handle, particularly to a handle having liquid styptic dispensing means therein.

It frequently happens during shaving with a safety razor that the user will inadvertently slide the razor sideways or otherwise manipulate it in a manner and to such an extent that the skin is cut slightly. Small projections on the skin are also often cut slightly when shaving with a safety razor even under optimum conditions of use. Such cuts are characterized by profuse and prolonged bleeding unless treated promptly with a styptic, such as alum. For this reason it is common practice for men who shave regularly to keep a supply of a styptic or astringent, generally a stick or "pencil" of alum, at hand which can be applied to a razor cut to stop bleeding. This necessitates an additional article to be included among the already numerous articles necessary for shaving and is thus undesirable. Furthermore, such alum sticks are seldom kept in a container and thus tend to contaminate and corrode other articles with which they come in contact. This is particularly disadvantageous for travelers as is readily apparent.

A further and principal objection to the use of a solid styptic or astringent agent for treating cuts or wounds in the skin is due to the fact it must be rubbed into the wound so that sufficient of the agent can dissolve in the fluids in the wound to exert the desired effect. This is often painful, especially after the piece of styptic has been used and its surface has become roughened. Furthermore, the repeated use of a styptic pencil is liable to lead to the introduction into the wound of certain types of infectious organisms which are not devitalized by the particular styptic substance used.

It has been suggested to incorporate a container for a styptic pencil in the handle of a razor so that the styptic would at all times be at hand when needed and would not become misplaced and so that its storage between uses would be facilitated and certain of the above-mentioned disadvantages overcome. However, none of the handles suggested have been adapted to the use of a liquid styptic, astringent or antiseptic and the principal objection to the use of solid astringents has therefore not been overcome by such devices. Even in the case of handles adapted to contain styptic pencils, the pencil must be removed from the handle before using and its use is, therefore, unhandy and devoid of desirable automatic features.

It is, therefore, an object of the present in-

2

vention to provide a handle for a razor adapted to contain a liquid styptic, astringent or antiseptic.

An additional object is to provide a razor handle adapted to dispense a liquid astringent automatically and at a controlled rate.

An additional object is to provide a razor handle for containing and for applying a liquid astringent to an open wound with a minimum of irritation of the wound.

These and related objects are accomplished readily and economically by providing in the handle of a razor, preferably a razor of the "safety" type having a shaving head in which a new blade can be inserted when the old one has become dulled, a receptacle for containing a fluid styptic, antiseptic or astringent, herein referred to generically as an "antiseptic," and means associated therewith to dispense the fluid antiseptic on the skin surface, or in a wound or abrasion therein, by merely contacting the dispensing means lightly with the area which it is desired to treat with the antiseptic. To prevent the application of undue amounts of the antiseptic, e. g. by inadvertent and undesired "flooding" of the antiseptic onto the treated area, means are provided to regulate the rate of flow of the fluid antiseptic during the application thereof and, to prevent loss of fluid by accidental spillage or evaporation, means are usually provided for sealing the device against such loss between uses, such means preferably operating automatically in such fashion that the device is normally sealed except when fluid is actually being dispensed therefrom.

Figure 1 is an elevation, principally in section, of a razor having a handle embodying one modification of the invention.

Figure 2 is an elevation, partly in section, of a dispensing razor handle embodying an alternative modification of the invention.

Referring now to Figure 1, there is shown a razor having a conventional shaving head comprising blade-clamping members 10 and 11, a blade 12, and positioning studs 13 secured, e. g. by a threaded stud 31 in conventional fashion, at one end of the main body member 14 of a handle comprising one modification of the invention.

The handle body member 14 is formed to comprise a receptacle, chamber or cavity 15 for holding a fluid antiseptic. The handle body member 14 is usually cylindrical but may be square, rectangular or of any other convenient or desirable cross-sectional shape and the fluid chamber is generally elongated to enable a suitable supply of liquid to be contained therein.

The chamber 15 is closed at its outer end, i. e. at its end farthest removed from the shaving head, with a dispenser body member 16, conveniently a somewhat elongated annular body threaded externally on its inner end and adapted to be screwed into threads 17 formed internally at the outer end of the hollow section of the handle body member 14. A dispenser body bore 18, preferably cylindrical in cross-section, extends longitudinally through the dispenser body member 16 and is constricted somewhat and formed at its outer end to provide an annular seat 19 facing inwardly of the bore and adapted to receive a smooth surfaced ball 20 having a diameter somewhat less than the diameter of the bore 18 to form a liquid-tight seal. The annular seat 19 is preferably of a suitable diameter to permit the ball 20 to project substantially beyond the farthest outward extension of the dispenser body member 16 and the outer end 21 of the dispenser body member is preferably rounded and otherwise formed and polished so as to present with the exposed surface of the ball 20 a smooth, substantially continuous surface which causes a minimum of irritation when rubbed gently over an abrasion or open wound.

A tubular piston 22 open at its inner end is positioned in the longitudinal bore 18 of the dispenser body 16 and is of such a diameter that it slides easily in the bore. The outer end of the piston 22 is closed with a piston head 23, which is conveniently flat and which contains one or more piston head ports 24 to permit free flow of fluid through the piston head 23. At least one of the piston head ports 24 is located off-center so that it is not closed when the piston head 23 and the ball 20 are in firm contact. A spring 25, conveniently a coiled spring under compression, is positioned inside the tubular piston 22 and bears at its outer end on the inside of the piston head 23. The inner end of the dispenser body bore 18 is closed with a spring-retaining member 26, against which the inner end of the spring 25 bears and which is secured in the bore 18 in any convenient fashion and provided with one or more spring-retaining member ports 27 permitting free flow of fluid between the fluid chamber 15 and the dispenser body bore 18.

The spring-retaining member 26 can conveniently be a close fitting plug which is pressed into position or it can be a threaded member which can be secured by means of threads formed in the surface of the bore 18. The spring-retaining member 26 is preferably adapted, e. g. formed with a flange 28 at its inner end somewhat greater in diameter than the diameter of the dispenser body bore 18, to extend only to a predetermined distance into the bore 18.

Under normal conditions of storage and use of the razor, the tension of the spring 25 keeps the piston head 23 tightly pressed against the ball 20 thus pressing the latter firmly against the annular seat 19 to seal the device and prevent passage of liquid or vapor between the ball and the seat. When, however, the ball is rubbed or rolled along the skin, as in treating a small cut, the spring 25 is depressed slightly by the pressure of the skin on the ball and the ball is displaced from its seat sufficiently to allow a thin film of liquid to adhere to the ball and to be deposited on the skin as it rolls along the surface of the skin.

To limit the rate of flow of the liquid to a desired predetermined value and to avoid its flooding onto the skin, it is preferable that the wall of the piston 22 be of such a length that it

abuts against the spring retaining member 26 when the tubular piston 22 has moved inwardly for a predetermined distance in the bore 18 and the ball has been unseated to the desired extent. 5 A travel of a few thousandths of an inch for the piston will generally be sufficient.

Liquid styptic or other agent can be loaded into the chamber 15 by disconnecting the dispenser body member 16 from the handle body member 14, as at 17, and filling the chamber 15 as desired. 10 To prevent leakage, a thin gasket 29 can be employed in conventional fashion between the dispenser body 16 and the handle body member 14. A cap 30 of conventional design can be removably 15 secured, e. g. by friction, over the outer end of the dispenser body 16, if desired, to protect the ball 20 and the polished surface 21 when not in use.

In an alternative arrangement of the parts as 20 shown in Figure 2, the dispenser body member 16 is connected with, e. g. by being pressed or threaded into the outer end thereof, a receptacle member 32 having a receptacle 36 therein which is separate from the handle body member 14 and 25 which is secured therein in any convenient way, e. g. by threads 33. The inner end of the receptacle member 32 can be closed in convenient fashion as by a threaded or friction plug 34. A fine capillary opening or port 35 can be drilled 30 in the plug 34, if desired, to assist in equalizing pressure between the receptacle 36 and the cavity 15 in the handle body member 14. Equalization of the pressure in the receptacle 35 with the atmospheric pressure is generally effected 35 when the ball 20 is unseated for the application of the antiseptic.

Although the preferred applicator means comprises a ball arranged substantially as in Figure 1, other applicator means can be used, if desired, 40 provided limiting the rate of flow of the antiseptic during use of the device to prevent flooding is effected. An alternate arrangement can comprise a wick suitably constricted to limit the rate 45 of flow of the antiseptic to a desired value or other means equivalent thereto.

I claim:

1. A razor handle comprising in combination a handle body member having a receptacle closed 50 at its inner end for containing a fluid, a dispenser body member secured to the outer end of the handle body member and closing the outer end of the receptacle, a longitudinal dispenser body bore through the dispenser body member communicating with the receptacle at its inner end and constricted at its outer end to form an annular ball seat, a tubular piston in the bore adapted to slide easily therein and closed at its outer end with a head having a port for the flow 55 of liquid therethrough, a ball retained between the piston head and the annular ball seat and adapted to form a liquid-tight seal when seated on the latter, spring-retaining means secured to the inner end of the dispenser body bore having a port for the flow of fluid therethrough, and 60 spring means under compressive stress positioned inside the tubular piston and bearing on the spring-retaining means and on the piston head for maintaining the piston head and ball normally in firm contact with one another and the ball firmly seated, the ball projecting through the annular ball seat and being movable inwardly of the bore against the pressure of the said spring means in response to external pressure to allow 65 passage of fluid between the ball and the seat.

5

2. The combination as claimed in claim 1 where-
in the spring-retaining means is positioned so as
to limit the inward travel of the piston and of the
ball in response to external pressure on the ball
and prevent flooding between the ball and seat
of a fluid contained in the fluid receptacle. 5
